UNITED STATES PATENT OFFICE.

RUFUS LEACH, OF CLARK'S ISLAND, ASSIGNOR OF FIVE-EIGHTHS TO EDWARD A. BUCK AND ALBION C. BATCHELDER, OF BANGOR, MAINE.

ROTARY PUMP.

SPECIFICATION forming part of Letters Patent No. 445,318, dated January 27, 1891.

Application filed December 20, 1888. Serial No. 294,170. (No model.)

To all whom it may concern:

Be it known that I, RUFUS LEACH, a citizen of the United States, residing at Clark's Island, St. George, in the county of Knox and State of Maine, have invented a new and useful Rotary Pump; and I do hereby declare that the following is a full, clear, and exact description of the invention, which will enable others skilled in the art to which it applies to make and use the same.

My invention relates to rotary pumps; and it consists in the improved construction of the same, as will be hereinafter more particularly described, and pointed out in the claim.

Throughout the description reference is made to the accompanying drawings, in which—

Figure 1 represents a vertical longitudinal section of my improved pump showing its interior construction. Fig. 2 is an isometric view of the sliding abutment used in my pump. Fig. 3 is a vertical cross-section of my improved pump cut through the dotted line y y of Fig. 1, and showing the same relative position of its internal parts as represented in the first figure.

Similar letters of reference refer to correspondingly like parts throughout the different views.

C designates a drum of elliptical shape centrally mounted on a shaft S and rotating therewith inside of an inclosing casing having a circular wall N, the inner diameter of which is equal to the length of the greatest diameter of said drum. This drum C is constructed with parallel sides. Its elliptical surface or periphery is planed at right angles to its sides, and one of the latter is provided with a concentric groove d of sufficient size and depth to admit a small roll e, attached to one leg of the sliding abutment B, as will be hereinafter explained. At opposite ends of the transverse axis of the elliptically-shaped drum C are cut small grooves a a, running transversely across its surface at these points and adapted to be filled with and hold packing. This drum C is situated within a shell consisting of two side plates A A, separated by a circular wall or partition N, provided with two openings or apertures E and G, one used for ingress and the other for egress orifices,

as shown by the arrows in Fig. 1. These openings E and G in the wall N of my pump may be situated anywhere upon the same, it making no material difference where they are located, and either may be used for induction or ejection orifices; but in the present case I have shown their entrance into the wall of the shell at very near a tangent to its circular interior, which situation I find as effective as any. The interior of the circular wall N forming part of the shell of my pump is bored out to a radius equal to one-half of the length of the long diameter of the elliptical drum C, into which the latter is fitted and rotated. The thickness of the said drum determines the width of the wall N, and also determines the capacity of the pump when taken in conjunction with the difference between its long and short diameters. This exact correspondence between the inner diameter of the circular wall N and the greatest diameter of the drum C effectually cuts off the lower part of the interior of the casing from the upper part thereof when the drum is in the position shown in Fig. 1. The advantage of this construction will be hereinafter set forth in describing the operation of the machine.

The side plates A A are made of suitable size and shape to cover each side of the circular wall N, to which they are bolted or otherwise secured, water or air tight. These side plates have a central hole drilled through each, through which the shaft S passes, and they may be cast with a boss around these shaft-openings which can be threaded and a hollow nut h turned thereon, forming a stuffing-box around the shaft S, as shown in Fig. 3, if desired, in this case forming air-tight journals around the said shaft. Though for ordinary pumping, such as water alone, I do not consider it absolutely necessary to construct such air-tight boxes, as the sides A A bear closely upon the revolving drum C, and fitting so snugly to the latter will make it impossible for water to pass between them to enter the journals, in which case a simple journal-box consisting of a hole bored through the sides A A the same size as the shaft S will answer the purpose.

Situated between the inlet and outlet openings E and G is an abutment B, arranged to

slide radially in a direct line from the center of the shaft S. This abutment forms a partition between the openings E and G, and it is provided with two legs c and c', which project downward from each end. These legs may be formed in one piece with the abutment, or made separate and bolted to each end of the latter, as shown in Fig. 2 of the drawings, and the distance between the legs c c' is equal to the width of the drum C, which revolves between them, and the under edge of the abutment, where it bears upon the surface of the said drum, is provided with a longitudinal slot, which is filled with packing f, to increase its frictional contact.

In order to hold and allow the abutment B, which is a little longer than the distance between the two sides A A, to slide within the latter, a radial groove b (partly shown in Fig. 20 3) is planed in the interior surface of each side A at this place the depth and thickness of the legs c and c'. These grooves are of sufficient length to allow the lower edge of the abutment to rest upon the surface of the elliptically-shaped drum C at all positions of the latter, and to maintain a constant contact upon the same. One leg c of the said abutment is provided with a small roller e, attached thereto by means of a bolt passing therethrough, upon which it turns.

The roller e projects inward at right angles from the leg c, and its size is governed by the size of the concentric groove d in the drum C, within which it rotates, by means of the revolutions of the said drum. It therefore is situated upon the leg c the same distance from the lower edge of the abutment as the interval between the surface of the drum C and the concentric groove d cut in its side.

To provide a sufficient distance for the abutment B to slide within the interior of the pump without projecting through the wall N, the latter is cast with an extension H projecting above its circular exterior, and containing continuations of the grooves b b in the sides A to allow and permit the reciprocation of the said abutment.

A cap I is bolted to and extends over the top of the extension H to prevent the outlet 50 of the liquid being pumped, provided any should happen to work through.

The operation of my improved rotary pump is as follows: The shaft S having been connected with some suitable power medium is 55 revolved thereby, turning the elliptical drum C within the circular chamber of the shell. The packing in the ends of the drum rubbing upon the interior of the wall N causes a vacuum and creates a suction through the inlet of the chamber. If the drum is 60 revolved from right to left, as shown in Fig. 1

of the drawings, a suction will be formed in the direction of the arrows through the inlet E, and behind the sliding abutment B. The opposite end of the drum, which is also suitably packed, forces the air before it against the sliding abutment B, and out through the egress-opening G, the abutment B in the meantime being kept in contact with the elliptical surface of the drum by means of the roller e, attached to one of its legs c, turning in the concentric groove d, as hereinbefore described. As the opposite end of the drum rises toward the abutment it forces the latter upward in the grooves b b in the sides A A, and at the time there is the greatest pressure but a small portion of the abutment is in contact with that pressure. When the long diameter of the elliptical drum passes by the said abutment, this end commences to draw through the ingress-opening, and the opposite end forces the liquid through the egress-orifice, and at the time the suction end passes by the ingress-opening it cuts off the suction of the opposite end and the space F 85 between the two is filled with compressed liquid, thus making the pressure equal each side of the forcing end of the drum, greatly relieving the same, forming a cushion, as it were, by keeping a constant even pressure 90 upon the power medium. Thus the pump is run smooth and without the disagreeable jerky movement common to a great many.

Having thus described my invention, what I claim, and desire to secure by Letters Patent 95 of the United States, is—

In a rotary pump, the combination, with the casing consisting of the centrally-perforated side plates, each having a radial groove extending from near the perforation to the circumference, and a circular wall between the plates having an inlet and an outlet opening substantially at a tangent to the ring, and a slotted portion between the inlet and outlet openings, which extends from the inner diameter out beyond the exterior diameter, said slot registering with the grooves in the side plates, of a shaft through the casing, an elliptical drum on the shaft, the length of which is equal to the diameter of the casing, and having a groove in one side, a flat abutment in the slotted portion of the ring of a greater length than the width of the drum, and a leg on each end of the abutment, which fits within the grooves in the side plates, and one of which is provided with a roller which fits within the groove in the side of the drum, substantially as described.

RUFUS LEACH.
